US0D1056055S

(12) **United States Design Patent** (10) **Patent No.:** **US D1,056,055 S**
(45) **Date of Patent:** **** Dec. 31, 2024**

(54) **CARD DEALER**

(71) Applicant: **Chenzhou Yihang Technology Co., Ltd**, Chenzhou (CN)

(72) Inventor: **Yiyuan Li**, Chenzhou (CN)

(73) Assignee: **Chenzhou Yihang Technology Co., Ltd**, Chenzhou (CN)

(**) Term: **15 Years**

(21) Appl. No.: **29/955,026**

(22) Filed: **Jul. 30, 2024**

(51) LOC (14) Cl. **21-01**

(52) U.S. Cl.

USPC **D21/396**

(58) **Field of Classification Search**

USPC **D21/396, 392**

(57) **CLAIM**

The ornamental design for a card dealer, as shown and described.

DESCRIPTION

FIG. 1 is a top, front, right side perspective view of a card dealer showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

(Continued)

The broken lines show the features of the card dealer that form no part of the claimed design.
